UNITED STATES PATENT OFFICE

153,648

DESIGN FOR A SCREEN BUILDING FOR AN OUTDOOR THEATRE

Samuel Herbert Taylor, Jr., Merchantville, N. J., assignor to Park-In Theatres Company, Camden, N. J., a limited partnership

Application April 21, 1947, Serial No. 138,527

Term of patent 14 years

(Cl. D13—1.2)

To all whom it may concern:

Be it known that I, Samuel Herbert Taylor, Jr., a citizen of the United States, residing at Merchantville, in the county of Camden and State of New Jersey, have invented, a new, original, and ornamental Design for a Screen Building for an Outdoor Theatre, of which the following is a specification, reference being had to the accompanying drawings, forming part thereof.

In the drawings:

Figure 2 is a perspective view from the inside of the theatre showing the other side of the screen building.

The dominant features of my design reside in the portion shown in full lines.

I claim:

The ornamental design for a screen building for an outdoor theatre, as shown and described.

SAMUEL HERBERT TAYLOR, JR.
